LIFTING JACK

Alvin L. Johnsen, Ottawa Hills, Ohio, assignor to
The American Forging & Socket Company,
Pontiac, Mich., a corporation of Michigan

Application September 1, 1937, Serial No. 161,881

8 Claims. (Cl. 254—98)

This invention relates to jacks but more particularly to lifting jacks such, for example, as are adapted to engage and lift the bumpers of automobiles, thereby to raise the vehicle.

An object of this invention is to produce a jack having a load-sustaining member which is movable forwardly along a bar or rod during the advancing or lifting movement and cooperates with the rod for supporting the load in the intervals between the advancing or lifting operations, such member being adapted to cooperate with the bar for effecting the retracting or lowering movement of the load upon relative rotation of these parts.

Another object is to produce a jack in which the load is raised or advanced by recurrent lever operations and is retracted or lowered by relative rotational movements of the parts.

A further object is to produce a vehicle bumper engaging jack which embodies a screw-threaded rod with which lever means cooperates for recurrently lifting the bumper, the construction being such that rotation of the rod effects retracting or lowering movement of the bumper.

A still further object is to produce a jack for automobiles and other uses which is simple and sturdy in construction, reliable in operation, inexpensive to manufacture, easy to assemble and contains the new and improved features of construction, arrangement and operation herein-after described.

A still further object is to produce a jack of this character in which lifting is accomplished by lever means cooperating with a screw-threaded rod and lowering by rotation of the rod, a tensioned part of the jack yielding radially to enable advancing or lifting movement of the jack and for sustaining the load after lifting has been accomplished and also cooperating with the rod upon turning movement thereof to cause retracting or lowering of the load.

For purposes of illustration but not of limitation, embodiments of the invention are shown on the accompanying drawings in which:

Figure 1 is a side elevation, partly in section, of a lifting jack, the parts being shown in the position assumed during the advancing or raising step, some of the parts being broken away to show the load-sustaining nut and associated parts and the manner in which the lever-actuated pawl engages the threads on the rod;

Figure 2 is a transverse sectional view on the line 2—2 of Figure 1;

Figure 3 is a fragmentary view of the upper end of the screw-threaded rod showing the op-

erating handle attached thereto for actuating the rod to lower the jack;

Figure 4 is a side elevation of an alternate form of jack in which a pair of pivotally mounted load-sustaining members are employed; and

Figure 5 is a fragmentary vertical sectional view showing the load-sustaining members and associated portions of the jack.

Referring to the drawings, the jack comprises a dome-shaped base 19 having a depression 11 in the top to receive the rounded end of a rod 12. The rod 12 is free from connection with the base 19 and is adapted to rotate relatively thereto. Formed on the rod are helical screw threads 13, the screw threads being buttress screw threads 15 for a purpose which will hereinafter appear. Mounted on the rod 12 is an elongate sleeve or housing 14 on the upper end of which is swivelly mounted a collar 15 which rests against an annular flange 16, a depending portion 17 integral with the collar engaging the flange 16. Projecting laterally from the collar is an integral arm 18 which is recessed to engage an automobile bumper or the like.

Extending laterally from an intermediate portion of the sleeve 14 is an enlargement 19 to which a lever arm 20 is pivoted upon a pin 21. The lever arm 20 is formed with a socket 21a to receive an end portion of a handle 22. As indicated in Figure 3, the handle 22 has a bend 23 so that it can be used as a crank for a purpose which will hereinafter appear.

Pivoted at one end on a pin 24 adjacent the pin 21 is a pawl 25 the end of which extends through an opening in the sleeve 14 and engages the screw threads 13. A coil spring 26 yieldingly urges the pawl 25 into engagement with the threads 13. It will be apparent that upon swinging movement of the lever arm 20, the sleeve 14 is advanced step by step upwardly along the rod 12, the pawl 25 successively engaging the threads 13 on the rod for effecting this movement.

The sleeve 14 and load supported thereby is supported during the upward swinging movement of the lever arm 20 by a load-sustaining member 27 which is disposed in an enlargement 28 projecting outwardly from the sleeve 14. The load-sustaining member 27 consists of a rectangular nut having internal screw threads fitting the screw threads 13 on the rod 12. The nut is separated into parts 27a and 27b which are urged toward each other and intimately into engagement with the threads 13 by leaf springs, a leaf spring 29 being secured by a screw 30 to the part 27a and bearing against the outer por-

tion of the enlargement 28. A similar leaf spring 31 similarly connected to the part 27b abuts against lugs 32 extending inwardly from the walls of the sleeve 14. The upper ends of the nut parts 27a and 27b are formed with complementary inwardly tapered portions 27c which together provide a surface slightly larger than the bore of the housing.

Within the enlargement 28 is a cavity 33 which affords a limited amount of movement to the load-sustaining member 27 in a direction longitudinally of the rod 12. The upper portion of the cavity 33 is formed with a recess 34 into which the member 27 is adapted to fit, the 10 tapered portion 27c of the nut parts 27 being adapted to bear against a tapered seat 34a adjacent the recess 34. It is apparent that when the sleeve 14 is advanced or moved upwardly along the rod 12 by the lever actuated pawl 25, the parts 27 and 28 yield radially and slip over the buttress threads 13 but upon release of the pawl 25 when the lever arm 20 is released or swung upwardly, the sleeve 14 rests upon and is supported by the load-sustaining member 27 20 which is securely held in the recess 34 and transmits the load to the threads 13. During this operation the seat 34a of the housing bears against the tapered portions 27c, insuring against lateral movement between the two parts of the nut 27. 25

In this manner it is apparent that progressive or step by step advancing movement of the sleeve 14 may be effected along the rod 12.

In order to lower or retract the sleeve 14, the upper end of the screw-threaded rod 12 is formed with a squared opening 35 into which fits a similarly shaped extension 36 on the end of the handle 22. Thereupon by turning the handle 22 which in this instance serves as a crank, the rod 12 is rotated and since the load-sustaining member 27 is held in place by the load imposed upon it and due to its frictional engagement with the sleeve 14, the sleeve is moved downwardly along the rod.

In the form shown in Figures 4 and 5, the spring-tensioned lever actuated pawl 25a operates in the same manner as the pawl 25 above described. The rod 12a has buttress screw threads 13a as above described so that the sleeve 14a is similarly advanced or raised in order to lift the rod. However, instead of a split nut, a different form of load-sustaining device is employed. In this instance, a pair of opposed arms 37 are pivotally mounted at their upper ends on pins 38 carried by projections 39 of the sleeve 14a. The free ends of the arms extend through slots 41 in the sleeve 14a into engagement with the threads on the rod 12a. The arms are urged inwardly into engagement with the threads on the rod 12a by coil springs 40 which encircle the pins 38 and abut respectively against the arms and the sleeve 14a. The rod engaging ends of the arms 37 are threaded to correspond with the threads 13a. When the sleeve 14a is advanced or moved upwardly along the rod 12a, the arms 37 slip over the threads and when the load is released, the arms 37 cooperating with the threads 13a support the load.

It will be understood that the sleeve 14a is lowered or retracted by rotating the rod 12a in a manner above described, the arms 37 sustaining the load during such lowering movement.

It is to be understood that numerous changes in details of construction, arrangement and 75 operation may be effected without departing from

the spirit of the invention especially as defined in the appended claims.

What I claim is:

1. In a jack of the character described, a rod having buttress screw threads, a load-receiving member on said rod, lever actuated spring tensioned pawl means for recurrently advancing said member, a load sustaining device carried by said member and having opposed spring tensioned internally screw-threaded parts urged into engagement with the threads on said rod, and means to impart relative rotation between said rod and load-sustaining device for retracting the latter. 5

2. In a jack of the character described, a rod having buttress screw threads, a load-receiving member on said rod, lever actuated spring tensioned pawl means for recurrently advancing said member, a load-sustaining nut carried by said member internally screw-threaded to fit the threads on said rod, said nut being formed in sections separable radially away from said rod, spring means normally urging said sections toward the rod, and means to impart relative rotation between said nut and rod for retracting the 25 nut and load-receiving member. 20

3. A jack including a screw-threaded rod, a load receiving member on the rod, lever actuated means for advancing said member, sectional threaded load sustaining means carried by said member and movable longitudinally thereof for engaging the screw threads of the rod, and means carried by the member which upon downward movement of the load sustaining means automatically moves and holds the sections thereof in engagement with the screw threads of the rod and which upon upward movement of the load sustaining means are released from the automatic means and are moved by the threads of the rod 30 out of operative engagement with said threads. 35

4. A jack in accordance with claim 2, wherein the nut sections are movable longitudinally of the load-receiving member and wherein there are complementary means between the nut sections and said member for causing the sections to move and be held in engagement with the rod threads upon relative longitudinal movement between the nut sections and member in one direction and to be released upon longitudinal movement in a 45 reverse direction. 50

5. A jack in accordance with claim 2, wherein the nut sections are movable longitudinally of the load-receiving member and wherein there are complementary means between the nut sections and said member for causing the sections to move and be held in engagement with the rod threads upon relative longitudinal movement between the nut sections and member in one direction and to be released upon longitudinal movement in a 55 reverse direction, and wherein said complementary means consist of tapered portions receivable one within the other to have a camming action therebetween. 60

6. In a lifting jack, in combination with a support, a threaded shaft rotatably mounted thereupon, a load-carrying member slidable along said shaft over the threads, means including a lifting element successively engageable with said threads as the load-carrying member moves along the 70 shaft, said lifting element being movably mounted in said load-carrying member and arranged to ratchet over said threads to prevent reverse movement of said member, means including a lever for actuating said lifting element to force 75

- the load-carrying member along the shaft, separate pawl means carried by said member and reacting against said threads in the same direction as said lifting element, means constantly urging said pawl means into engagement with said threads, and means for turning said shaft with relation to the pawl means, whereby said pawl means may act as a nut to react against the threads and force said member along the shaft.
- 5 7. Means as set forth in claim 6 in which said pawl means comprises a divided nut having complementary sections movable to and from engagement with said threads, said threads being substantially of buttress form, whereby said nut sections may ratchet thereover in one direction, and
- 10 10. Means as set forth in claim 6 in which said pawl means comprises a divided nut having complementary sections movable to and from engagement with said threads, said threads being of buttress form, whereby said sections may ratchet thereover in one direction, and means urging said sections into engagement with the shaft.
- 15 15. Means as set forth in claim 6 in which said pawl means comprises a divided nut having complementary sections movable to and from engagement with said threads, the threads being of buttress form, whereby said sections may ratchet thereover in one direction, and means urging said sections into engagement with the shaft.

means urging said sections into engagement with the shaft.

8. Means as set forth in claim 6 in which said lever is pivoted on said load-carrying member, and said lifting element comprises another pawl pivoted on said lever near said shaft, spring means constantly urging said lifting element pawl into engagement with said threads, said first mentioned pawl means comprising a nut formed in complementary radially divided sections movable to and from the threads, the threads being of buttress form, whereby said sections may ratchet thereover in one direction, and means urging said sections into engagement with the shaft.
